CLAIM

I claim the ornamental design for a laptop docking station holder, as shown and described.

DESCRIPTION

FIG. 1 is an upper perspective view of a front side of a laptop docking station holder in accordance with the present design;

FIG. 2 is a top plan view of the laptop docking station holder of FIG. 1;

FIG. 3 is a bottom plan view of the laptop docking station holder of FIG. 1;

FIG. 4 is a right side plan view of the laptop docking station holder of FIG. 1;

FIG. 5 is a left side plan view of the laptop docking station holder of FIG. 1;

FIG. 6 is a rear plan view of the laptop docking station holder of FIG. 1;

FIG. 7 is a front plan view of the laptop docking station holder of FIG. 1; and,

FIG. 8 is a bottom perspective view of a rear side of the laptop docking station holder of FIG. 1.

Directional terms (such as top, bottom, etc.) are made with regard to the laptop docking station holder as shown and positioned in the drawings and are not intended to limit the scope of the invention.
